Irving Harper, Rye, N.Y., assignor to Howard Miller
Clock Company, Zeeland, Mich., a corporation of
Michigan

Filed Mar. 26, 1962, Ser. No. 69,438

Term of patent 14 years

(Cl. D48—14)

FIG. 1 is an elevation of a decorative element for lighting fixtures and the like showing my new design;

FIG. 2 is a side view of the element of FIG. 1 and showing the three bottom frusto-cones in section;

FIG. 3 is an end view of the element shown in FIG. 1; and

FIG. 4 is a perspective view of the element shown in FIG. 1 illustrating an environmental use as a part of a lighting fixture in association with a frame and similar elements, the latter shown in dashed lines.

I claim:

The ornamental design for a decorative element for lighting fixtures and the like, substantially as shown and described.
